CLAIM

The ornamental design for a shaving razor guard bar as shown and described.

DESCRIPTION

FIG. 1 is a top perspective view of a shaving razor guard bar showing our new design;
FIG. 2 is a top view thereof;
FIG. 3 is a bottom view thereof;
FIG. 4 is a right view thereof;
FIG. 5 is a left view thereof;
FIG. 6 is a rear view thereof;
FIG. 7 is a front view thereof; and,
FIG. 8 is a top perspective view thereof, shown in an environment of use.

In FIGS. 1-7, the broken lines illustrate portions of the shaving razor guard bar forming no part of the claimed design. In FIG. 8 the broken lines illustrate environmental subject matter only and form no part of the claimed design.

1 Claim, 8 Drawing Sheets
